UNITED STATES PATENT OFFICE.

CARLO DALBONI, ANNIBALE GASPERETTI, AND RAIMONDO ALBANESE, OF NEW YORK, N. Y.

LOCK.

1,325,510.

Specification of Letters Patent. Patented Dec. 23, 1919.

Application filed March 27, 1919. Serial No. 285,446.

To all whom it may concern:

Be it known that we, CARLO DALBONI and ANNIBALE GASPERETTI, citizens of the United States, and RAIMONDO ALBANESE, a subject 5 of the King of Italy, all residing in New York, in the county of New York and State of New York, have invented certain new and useful Improvements in Locks, of which the following is a specification.

10 We have invented an improvement in locks; particularly a lock of the type which requires a combination of movements to be given to certain parts in order to unfasten the lock; the combination being susceptible 15 of change according to circumstances of use.

An object of our invention is to provide a lock comprising a latch or bolt upon which are mounted the parts which must be actuated in the proper manner and sequence before the latch or bolt can be withdrawn from effective position; such parts being capable of quick and easy manipulation by any one familiar with the lock, for the purpose 25 of operating or setting the same.

Other objects and advantages of our invention will be described in the following specification taken with the accompanying drawings; and the novel features of our lock 30 defined in the appended claims. This disclosure, however, is explanatory only, and we may resort to constructions different from what is actually shown herein, but within the scope and spirit of our invention, 35 to the full extent indicated by the general meanings of the terms in which the claims are expressed; and by variations in the phrasing thereof.

On the drawings:

40 Figure 1 is a front elevation of our complete lock;

Fig. 2 is a similar view with the bolt or latch removed;

Fig. 3 shows in front elevation, partly in 45 section, the latch or bolt detached;

Fig. 4 is a bottom plan of the bolt, partly broken away;

Fig. 5 is a sectional view of the knob and elements associated therewith for actuating 50 the lock;

Fig. 6 is a top plan of the bolt, in part;

Fig. 7 is a side view of a detail;

Fig. 8 is a section on the line 8—8 of 55 Fig. 3;

Fig. 9 is a section on the line 9—9 of Fig. 3;

Fig. 10 is a section on the line 10—10 of Fig. 3; and

Fig. 11 is a view showing some of the parts of our lock in the position they must be caused to assume to allow the bolt to be moved back.

The same numerals identify the same parts throughout.

In the drawings the numeral 1 indicates a support or base-plate upon which is slidably mounted a latch or bolt 2. This bolt moves upon projections 3 which are secured to the plate 1, and which engage the lower edge of the bolt or latch; while adjacent the top edge of this bolt we affix to the plate or support, a strip 4 which is undercut so that one edge of same will overlap and engage a rib 5 on the bolt 2. The projections 3 and strip 4 thus constitute a guideway in which the bolt 2 can move back and forth. In practice, the support 1 and all the other parts of the lock mounted thereon will be affixed to a door, for example, in such a manner that the parts presented in Fig. 1 will face the interior of the apartment which the door opens and closes; and the bolt will be adapted to project beyond one edge of the plate and the door carrying same, so that, when the door is closed, the bolt will prevent the door from being opened by engaging a striker-plate not shown, attached to the frame of the door, as understood by those skilled in this art. When the door is opened, the face of the lock presented in Fig. 1 will move toward the observer; and when the door is closed, it will move away from the observer; and the face of the bolt opposite that presented to the observer in Fig. 1, will be beveled as indicated in Figs. 4 and 6; to enable the lock to snap shut when the door is closed and one does not pause to manipulate the lock in order to make it engage the striker-plate above mentioned.

When the bolt or latch 2 is in engagement with the striker-plate, it can be withdrawn from effective position to enable the door to be opened, by means of a shaft 6 carrying a member or rigid arm 7 adapted to make contact with an element 8 carried upon the bolt 2. This element 8 is movable and it is provided with a portion or shoulder A; which, when the arm 7 engages the element 8 to withdraw the bolt, will be in juxtaposition with a portion of the arm 7, likewise marked by the letter A at the end of one side of the same. The extremity of the

arm 7 is rounded, and normally the element 8, which is movable with respect to the bolt 2, will be kept out of position to be engaged by this arm by certain movable parts to be described presently, on the bolt 2. The parts in question are adjustable and movable independently, and they must be actuated into position to release the element 8, and permit it to move toward the shaft 6 far enough for the arm 7 to strike against it and move the bolt backward. The shaft 6 is turned by means of a knob 9 which of course will be on the outside of the door; and the shaft projects through the same, and the plate 1 mounted thereon; and the arm 7 carried by the shaft 6 will be located so that the plate 1 is between it and the knob; and beyond the arm 7 this shaft will be engaged by a bracket 10 in the form of a bent strip secured to the plate at one end and providing a bearing for the shaft at the other. To advance the bolt into effective position, we employ a spring 11; which is seated in a socket on the plate 1, and abuts against the rear end of the bolt; acting to project it, so that its beveled end will extend far enough past the plate 1 to enable it to enter the striker-plate by which the lock holds the door shut.

As shown in Fig. 3, the bolt 2 has a pair of arms 12 extending rearward therefrom at the top and bottom. Parallel to each of these arms 12, and in proximity thereto, is a rigid spindle 13; affixed to the bolt and designed to carry the movable parts by which the position of the element 8 is controlled. The parts referred to comprise disks 14; two of these disks being shown carried by each journal 13 and located at the opposite ends thereof; and between the two disks on each of these journals are two gears 15. The disks 14 are cup-shaped, making their outside surfaces cylindrical, and are open at one end and closed at the other. Likewise the gears 15 are cup-shaped, being open at one end and closed at the other, but with bosses or hubs projecting from their closed ends and providing bearings which engage the journals 13; these bosses or bearings of gears 15, as shown in Fig. 3, extending through apertures in the closed ends of the disks 14 far enough to abut heads 16, which are pinned to the journals 13. These heads close the open ends of the disks 14, and inside of these disks are spiral springs 17 which hold the disks 14 and gears 15 in contact with each other. These springs 17 are merely compression springs, and are designed to permit the disks 14 to be rotated in order to adjust them and to enable the relative positions of these disks to be changed whenever it is desired to alter the combination of movements necessary to withdraw the bolt 2. Inside the gears 15 we also place spiral springs 18, affixed to

the gears at one end and the journal at the other. These springs 18 permit the gears to be rotated to a predetermined degree; but when the gears are released, the springs act to return them to their original positions. Between each two gears on the journals 13, is a head 19 which enters the open ends of these gears and carries a pin 20. From the adjacent sides of each gear, projects a small stud 21; and the springs 18, when they are mounted in the gears 15, are put under sufficient tension to hold the studs 21 against the pins 20; and to move the gears and separate the studs 21 from the pins 20, sufficient force must be applied to these gears to overcome the springs 18 for the time being. Similar studs 22 project from the closed ends of the disks 14 and enter the spaces between two adjacent teeth on the gears 15; thereby holding each disk 14 and the adjacent gear 15 rigid with each other. To change the relation of the disks with the gears, one merely moves the disks along the journal 13 with his fingers, far enough to disengage the studs 22, pressing the springs 17 for this purpose, and then turns the disks far enough to enable the studs to enter the space between any other pair of teeth on the gears 15. In this way, as soon as the disks are released, the springs 17 force the disks back into engagement with the gears, and when the gears are turned the disks must again turn with them.

To rotate the gears, we make the knob hollow and provide it with a member 23 which is mounted to reciprocate in the knob, and which projects from the front of same, so that, one turning the knob, upon taking hold of it with his hand, can press the member 23 inward with his thumb. This member 23 comprises a stem 24 which projects into the shaft 6 the latter being hollow, as indicated in Fig. 5. The inner end of this stem has a finger 25 which projects through a slot 26 in the shaft, into position to strike against the teeth of the gears 15; and a spring 27 in the knob 9 engaging the head of the member 23 where the stem is attached to this head; and a shoulder in the knob acts to hold the member 23 with the finger 25 at the rear end of the slot 26; giving it sufficient space to clear the gears when one does not desire to rotate them. On the shaft between the plate 1 and the bracket 10, is a notched disk 28 shown in Fig. 2; the disk being engaged by a pointed pawl 29 mounted in a guide 30 and forced toward the disk by a suitable spring. When this disk is in the position shown in Fig. 2, the finger 25 is in line with the lower gear at the right, as shown in Fig. 1. By turning the knob to make the pawl 29 engage the nearest notch, finger 25 will be brought into line to engage the lower disk at the left; then by turning the knob to rotate the disk farther

(clockwise with respect to Fig. 2), the finger can be brought into position to engage successively the upper gear at the left and the upper gear at the right; these positions being indicated to the operator in each case by the click of the pawl as it enters the recesses in the disk 28. Of course the knob may have a suitable mark or indication thereon, and the outside of the door may have a similar indication; and by bringing the two indications into line with each other, the operator will know that he has the finger 25 in position for the first gear 15. Then after turning the first gear, he turns the knob in the proper direction to operate the other three gears by turns, the right position being given by the click of the pawl against the disk 28 in each instance.

The element 8 is mounted to rotate upon a shaft or pivot 31, shown in Fig. 4; the edge opposite this pivot or shaft 31 being free to move up and down as indicated by the arrow in Fig. 1 and by the broken lines in Fig. 11. On the upper face of the element 8 is a pair of fixed projections 32 in line with the two lower disks 14, and arranged to enter a notch or recess 33 in the face of same. When the gears are turned to rotate these disks to bring the notches 33 opposite the points or projections 32, the element 8 is in readiness to move upward so as to move the part A far enough toward the shaft 6 to enable the part A on the arm 7 to strike against it and move the bolt 2 backward. This element also works in cooperation with similar parts rigidly secured to a spindle 34 mounted in bearings at the side of the upper arm 12; the parts in question being in the form of arms 35, likewise having projections 32 in line with the two upper disks, and designed to enter similar recesses 33 in the cylindrical faces of same. One end of this spindle 34 will have a crank 36 connected by a link 37 to a pin 38 rigidly attached to the element 8; and a spring 39 on the bolt 2 secured to this bolt at one end and to the link 37 at the other, tends to actuate this link so as to lift the element 8 and depress the arms 35 (see Figs. 1, 3 and 8).

On the spindle 34, between the rigid arms 35, we also mount a pair of pawls 40 having their ends in position to engage the teeth 15. These pawls are rotatably mounted on the spindle 34 but are normally forced downward toward the gears 15 by the springs 41; these springs being made rigid to the spindle 34 at one end, and being bent across the tops of the pawls at the other. To prevent the springs from forcing the pawls downward too far, the arms 35 may be connected by a member 42 on which the pawls 40 rest. Similar pawls 43 are pivotally secured to the element 8 in position to engage the teeth 15 of the lower gears 15, and they are pressed upward by springs 44 abutting these pawls at one end and the lower arm 12 of the bolt 2 at the other. Stops 45 prevent the springs 44 from moving the pawls upward too far, and the parts of these pawls which project above the top of the element 8, adjacent the points 32 enter the spaces between the gear teeth. These pawls permit the two gears at the top of Fig. 1, to be turned by the finger 26 on the member 23, in such a direction that the halves presented to the observer in Figs. 1 and 2, move upward; and the two lower gears to be moved by the finger 26 that the halves presented to the observer move downward; and the four pawls act to hold these gears against the return movement until the pawls release them when the arm 7 presses the element 8 downward, whereby the lower pawls are depressed and the upper ones lifted to clear the four gears.

To operate the lock when the door is closed, and when the projections 32 of the element 8 and the parts 35 are out of registry with the recesses 33 in the disks 14, the element 8 will be held down so far that the part A of the arm 7 will clear the part A of this element 8; and if the knob be turned, under these conditions, so as to move the arm 7 clockwise with reference to Fig. 1, the rounded extremity of this arm may make contact with the element 8 but will not withdraw the bolt 2. To undo the lock, one must press the member 23 to work the gears 15, and thereby carry the disks 14 so that the recesses 33 come into registry with the projections 32 on the element 8, and the parts 35. Then the spring 39 will actuate the element 8 and the parts 35 to cause the projections 32 to enter the recesses 33. Upon releasing the member 23, the knob can now be turned and the arm 7 will strike against the element 8 and pull the bolt 2 back out of effective position.

As indicated in Figs. 1 and 2 and more fully in Fig. 7, the cylindrical faces of the disks 14 will be marked from 0 to 9, the recesses 33 being located about where the numeral 3 would be placed; and the stud 22 being located opposite 0. When a disk is turned so that, with the stud 22 engaging the adjacent gear 15, the 0 mark is in central position as shown in the case of the upper disk at the right in Fig. 1, and the lower disk at the left in Fig. 3; the recesses 33 on the disks will be in line with the adjacent projections 32; but of course, the projections cannot enter the recesses on these two disks unless the other projections 32 are in line with the recesses on the other two disks. As shown in Figs. 1 and 3, the upper left disk is in such position that the numeral 1 is about in the same horizontal plane as the axis of the upper journal 13, and so is the lower disk at the right; hence these two disks must be actuated by turning the ad-

jacent gears a distance of one tooth to bring the notches 33 in these two disks, into registry with the adjacent projections 32; when, since the notches on the other two disks are 5 already in line with the adjacent projections, the four projections can then enter the four recesses in the disks simultaneously. Hence, with the parts in the position just outlined, the combination is 1010; that is to say, if 10 one starts with the lower disk at the right, he must turn the adjacent gear one tooth, the lower gear at the left, not at all; the upper gear at the left, one tooth; and the upper gear at the right, no teeth; in order to 15 have the proper combination. This combination can of course be changed by adjusting the disks 14 independently; and the number of teeth which must successively be engaged by the finger 25 in each gear 15, will 20 then be indicated by the number on the cylindrical face of the disk which is in middle position. To manipulate the disks 14 to adjust them, one can remove the bolt at will from the plate 1.

25 Whenever any one of the disks has the 0 mark in central position and engages the adjacent gear in such a manner that, with the stud 22 between two teeth on said gear, the spring 18 therein is free to hold the stud 30 21 on the gear against the pin 20, the three teeth which are located on the lower quarter presented to the observer, of each of the upper gears in Figs. 1 and 3, and the three teeth which are located on the upper quarter 35 of the two lower gears presented to the observer on the same two views, are cut away for fully half of their lengths. The total number of teeth is twelve, and the total number of complete teeth is nine; hence the 40 finger 25 cannot in any case engage more than nine teeth in succession; because after engaging nine complete teeth this finger will have reached the space over which the three remaining shortened teeth do not extend; 45 hence it cannot turn the gears farther, and thus breaking of the springs 18 by subjecting them to too much tension will be prevented. When a gear must be turned by pressing the finger 25 against nine teeth in 50 succession to bring the notch 33 in the face of the adjacent disk opposite the adjacent point or projection 32, the associated gear can be turned to the extent required but no farther. When each of the disks is in 0 position the stud 22 thereon will engage the 55 first of these cut-away teeth, beginning at the middle and extending downward with the upper gears, and at the middle and extending upward with the two lower gears.

60 After the proper combination of movements has been given to the disks 14 to enable the projections 32 to enter the recesses 33 therein, so that the arm 7 can move the bolt 2 back, one can reset the disks so as to hold the element 8 out of position 65 to be engaged by the arm 7, by turning the arm 7 in the opposite direction, in Fig. 1, that is counter-clockwise. Such a movement will force the element 8 downward, disengaging the points 32 thereon from the lower 70 disks and lifting the points 32 on the parts 35 from the upper disks; the springs 18 then acting to return the gears and the disks to starting positions. When a person enters a room or apartment provided with our 75 lock, he opens it as above described, by pressing upon the member 23 and turning the knob 9; and after going through the door he can close the door; resetting the combination at once before closing the door, or 80 closing the door without resetting the combination. In either case he can open the door again from the inside by means of a cam device 46 rotatably mounted in plate 1 on that face of the same which is presented 85 to the inside of the door, or apartment which is entered through the door. Of course whether the combination is reset or not, the door can be closed by simply pushing it shut, the beveled end of the bolt 90 enabling the striker-plate to force it back against the spring 11 and the spring 11 moving the bolt into engagement with the 95 striker-plate afterward. The device 46 is mounted upon a rotatable shaft 47 which may have a polygonal socket 48 to receive the stem of a knob, for instance, to turn this device; and this device may have a projection 49 to enter a recess 50 at the bottom of the bolt. Therefore, when the device 46 is 100 turned as indicated by the arrows in Figs. 1 and 2, the point 49 withdraws the latch 2. To hold the bolt shut, we provide a reciprocating stop 51 mounted in a bearing 52 on one of the projections 3 and engaged by a 105 spring 53 which forces it to project far enough into the path of the element 8, as indicated in Fig. 1. When the element 8 moves upward as far as it will go, upon the projections 32 entering the notches 33 of 110 adjacent disks 14, the element 8 will clear this stop 51; but otherwise the element 8 will not clear this stop when the latter is lifted by the spring 53 and thus the bolt 2 will be held in effective position and the door 115 kept closed until some one manipulates the knob from without in the proper manner, and the element 8 is permitted to rise high enough to be engaged as described by the arm 7 to clear the stop 51. In such a case, the door can be opened from without, by some one knowing the combination, but the lock cannot be forced open by a tool; and at the same time any one inside the door or 120 apartment to which the door leads, can withdraw the bolt 2 at will by turning the device 46. For this purpose, the device 46 in question, has a cam portion 54 which pro-

jects from one end toward the observer in Figs. 1 and 2; and the lower end of the stop will have a lug 55 extending into the path of this cam projection 54. Hence, by turning the device 46 the stop 52 will be depressed and the bolt can be opened from the inside of the apartment regardless of the position of the element 8.

We also provide a cam piece 56 mounted 10 on the block 3 adjacent the bearing 52 for putting stop 51 out of operative position when desired. This cam piece 56 is mounted on a pivot screw 57, and has an inclined edge 58 and a pin or knob 59 on one side 15 of the pivot screw 57. The opposite end of the cam piece 56 engages a lug 60 on stop 51 opposite the lug 55, and when the cam piece 56 is moved by forcing the pin 59 upward the stop 51 is retracted. When the 20 cam piece and the stop 51 are in the positions just referred to, the edge 58 will project into the path of the rear end of the lower arm 12 of the bolt 2; hence if the stop 51 be retracted, whenever the door is 25 slammed shut the cam piece 56 is forced to release stop 51; whereby whenever any one has opened the door and reset the disks 14 by turning back the arm 7 to make it necessary for them to receive the proper combination of movements to withdraw the bolt 30 2, the next person going out of the door and closing it, will be sure to shut it behind him with the stop 51 projecting upward far enough to prevent the door from being re- 35 opened except by working the combination from without. But any one on the inside of the door can open it at once by turning the device 46 which will shoot back the bolt 2 and depress the stop 51, as stated. The 40 extremity of the cam piece 56 adjacent the pin 59, can be engaged by a suitable bent resilient strip 62 which enters a notch in the cam piece and holds it in either upper or lower position. A stud 61 limits the 45 downward movement of the right end of the piece 56.

A pivoted catch 63 is mounted on the other block 3, and is engaged by a bent spring 64 to force it far enough to engage 50 the front end of the element 8 when this element is in the lowermost position. This catch 63 can be depressed to permit the bolt to be withdrawn but a stop-pin 65 holds it against upward movement beyond a certain 55 point; and when the projections 32 all engage the recesses 33 in the disks 14, the element 8 will clear the stop 63 and the bolt can then be withdrawn to adjust disks 14 without depressing the stop 65.

60 The catch 63 thus serves for arresting the forward movement of the bolt toward projecting or operative position; but when the element 8 clears this catch the bolt can be manually separated from the remainder of 65 the lock to enable one to adjust the disks

14 and thus change the combination whenever he so desires.

While four disks 14 may be utilized, the lock will work with two or three; the pawls 40 and the parts or elements 35 being omitted when only two are used. 70

Having described our invention, what we believe to be new and desire to secure and protect by Letters Patent of the United States is:—

1. In a lock, the combination of a bolt, a plurality of independently adjustable movable parts mounted on said bolt; a member for actuating the bolt to retracted position, an element carried by said bolt and controlled by said parts to be permitted to move into position to be engaged by said member, and means projecting into the path of said element to arrest the bolt when the same moves into operative position, said element 80 clearing said means when it is permitted by said parts to move into position to be engaged by said member; whereby said bolt can be manually removed from the remainder of the lock to enable said parts to be adjusted. 85

2. In a lock, the combination of a bolt, a knob having a shaft carrying a fixed arm for withdrawing said bolt; a reciprocating member mounted in said knob and said 95 shaft, a plurality of rotatable gears mounted upon the bolt to be actuated by said reciprocating member; a disk adjustably connected with each of said gears, to be turned by same, said disks having notches therein; and 100 elements disposed upon the bolt to be permitted to move by the notches in the disks into position to be engaged by the arm on the shaft of said knob, whereby said bolt can be caused by said arm to withdraw from 105 effective position.

3. In a lock, the combination of a bolt, a plurality of independently adjustable and movable parts mounted on said bolt; a member for withdrawing said bolt, and an element carried by the bolt and controlled by 110 said parts to be engaged by said member; said bolt, when said element is permitted by said parts to be engaged by said member, being removable from the remainder of the 115 lock.

4. In a lock, the combination of a bolt, a movable element carried thereby, a knob having a shaft carrying a rigid arm to engage said element and withdraw the bolt 120 from effective position, a plurality of rotatable gears mounted on the bolt, a reciprocable member in the knob and shaft to turn said gears; a disk having a notch adjustably connected with each of said gears, said 125 notches permitting said element to move into position to be engaged by the arm, a stop, a spring to project the stop into position to engage the element when the bolt is in effective position, and said element is out of po- 130

sition to be engaged by said arm; a cam piece to retract said stop, said cam piece being operable from one side of said lock and being engaged by the bolt when the latter is forced out of effective position to release the stop, whereby when the bolt moves into effective position the stop may prevent the withdrawal of the bolt; and a device oper-

able from one side of the lock to retract the stop and withdraw the bolt.

In testimony whereof we have signed our names to this specification this 14th day of March, 1919.

CARLO DALBONI.
ANNIBALE GASPERETTI.
RAIMONDO ALBANESE.
